UNITED STATES PATENT OFFICE.

JAMES L. MCQUARRIE, OF MONTCLAIR, NEW JERSEY, ASSIGNOR, BY MESNE ASSIGNMENTS, TO WESTERN ELECTRIC COMPANY, INCORPORATED, A CORPORATION OF NEW YORK.

MULTIPLE-BRUSH SWITCH.

1,177,044.

Specification of Letters Patent. Patented Mar. 28, 1916.

Application filed June 8, 1915. Serial No. 32,849.

To all whom it may concern:

Be it known that I, JAMES L. MCQUARRIE, a citizen of the United States, residing at Montclair, in the county of Essex and State 5 of New Jersey, have invented certain new and useful Improvements in Multiple-Brush Switches, of which the following is a full, clear, concise, and exact description.

This invention relates to switching apparatus for use in automatic and semi-automatic systems, and more particularly to panel switches of the multi-brush type, that is, switches each of which is provided with a plurality of brush sets any one of which may 15 be rendered operative in extending a call.

The principal object of this invention resides in the provision of improved means for tripping or rendering operative any desired one of the brush sets of a switch. Heretofore in switches of this type a brush tripping spindle and an operating magnet therefor have been provided for each switch. The present invention contemplates the provision of a plurality of tripping devices common to a group of switches, only as many tripping devices being provided as there are sets of brushes on any one of said switches. As the number of switches in a group is generally greatly in excess of the number of 30 multiple brush sets on a switch, this results in a material saving in the tripping devices and also provides certain operating advantages.

The switch structure, to which the present 35 invention is shown as applied, is of the general character described in the patent to E. B. Craft and J. N. Reynolds, No. 1,123,696.

Referring to the drawing, Figure 1 shows a side view of a portion of the switch; Fig. 40 2 is a plan view of one of the brush sets and an adjacent portion of the panel bank; Fig. 3 shows a portion of one of the common tripping devices and the relation of a pair of the individual trip elements thereon to the respective brush controlling levers of a pair of adjacent switches; Fig. 4 is a perspective view of one of the individual brush tripping devices or catches carried by a common trip rod; Fig. 5 shows a brush set and the manner in which the brush controlling lever 45 thereof engages the trip rod in order to restore the brushes to their inoperative position when the switch returns to normal.

In the drawings, 1 indicates the brush 55 shaft upon which is supported a plurality of

brush sets, usually five in number, although only two are shown in the drawings. Secured to this shaft are the brush sets 2, each of which consists of a plurality of brushes, four being shown in the drawings. Of these 30 four brushes, the two outermost are arranged to engage corresponding contacts in the panel bank while the two inner brushes engage on opposite sides of the middle terminal of the set in the panel bank. If desired, however, only two brushes need be provided each of which will engage its own individual fixed contacts.

Pivotedly supported adjacent to each brush set in any suitable manner is a brush 70 controlling member 3 formed in the present instance of a rebent strip of metal, the ends of which project rearward or toward the shaft 1. The lever 4 is arranged to be engaged by the tripping device to release the 75 set of brushes, and the lever 5 operates to restore the brushes to normal in a manner which will presently appear.

Projecting upwardly from the lever 3 adjacent to the springs or brushes is a pair of 80 insulating rollers 6 which, when the switch is in its normal position, are located between the innermost brushes of the set in order to hold the said brushes in their inoperative position. Between each inner brush and its 85 adjacent outer brush is an insulating block 7, by means of which the outer brushes are also moved to inoperative position.

As the driving or operating mechanism for the switch may be substantially the same 90 as that shown in patent to J. N. Reynolds, No. 1,103,623, it will be only briefly described herein.

Secured to the lower end of the shaft 1 is an elevating bar 8 which passes adjacent to 95 the power driven drums 9 and 10 rotating in opposite directions. On the opposite side of the bar 8 and adjacent to the drums 9 and 10 are the antifriction rollers 11 and 12, carried on the upwardly extending portions 100 of the armatures 13 and 14 respectively. Adjacent to each of these armatures is an electromagnet upon the energization of which the corresponding roller is operated to force the bar 8 into engagement with one 105 of the power driven drums 9 or 10.

The bar 8 is provided with a series of slots or notches 15 arranged to be engaged by the pivotally supported pawl 16, by means of which the shaft is held in its elevated or 110

operative position. Upon the energization of the release and down-drive magnet 17, the projection 18 carried by the armature thereof engages the downwardly extending end of the pawl 16, whereby the shaft is released so that it may be returned to its normal position by means of the drum 9.

All that part of the structure which has now been described is substantially the same 10 as described in the two patents above referred to.

The common trip feature which forms the principal object of this invention will now be described in detail. It is to be understood 15 that the shafts 1 of the group of switches are all mounted parallel to each other and in the same plane. Parallel to the plane of the shafts 1 and slightly below the brush sets 2 thereof, when the shafts are 20 in their normal position, are the common trip rods or shafts 19, there being as many of these rods as there are multiple brush sets upon any one of the switches. These rods are rotatably mounted in any desired manner. Secured to each of these rods 19 near one end thereof is a projecting lug or finger 20 arranged to be engaged by the outer end of the armature 21 of the trip magnet 22. Thus it will be seen that upon the energization 30 of a magnet 22, the corresponding rod 19 will be rotated in a clockwise direction as viewed in Fig. 3, and upon the deenergization of the magnet the rod will be returned to its normal position by means of the retractile spring 23.

Mounted on the rod 19 are the trip members 24, one being placed in proximity to each of the trip levers 4 of the adjacent brush sets. Each trip member or catch 24 40 comprises a member 25 rigidly secured to the shaft, and carrying at the upper end thereof the outwardly extending finger 26. Loosely mounted on the rod 19 with the flanges thereof on the opposite sides of the member 25, is the channel-like member 26 which is provided at the lower end thereof with the projecting finger 27. A spring 28 is connected at its opposite ends to the fingers 26 and 27 respectively, and by its tension tends to hold the member 26 in engagement with the shoulders 29 on the member 25. Each of the members 26 is provided at the upper end thereof with a projection or catch 30.

Now, if it is desired to release one of the brush sets of a switch, the corresponding magnet 22 is energized causing the shaft 19 to rotate as previously described, positioning the projections or catches 30 of the several tripping devices 24 over the trip levers 4 of all the corresponding brush sets of the switches of the group. The switch through which the connection is to be established is carried upwardly by the energization of 65 the power magnet associated with the drum

10. As the trip lever 4 of the selected set of brushes of the operated switch is in engagement with the catch 30, it will be prevented from moving upward in the initial movement of the switch. This will cause it 70 to rotate about its supporting pivot and thus move the insulating spacing devices 6 into the position shown in Fig. 5, when the brushes will be released and will assume a position to traverse the contact terminals of 75 their respective section of the switch bank. As the switch shaft moves upwardly, the lever 4 by engaging the catch 30 may cause a rear or backward movement of the member 26 against the tension of the spring 28. 80 As soon as the brush shaft has moved beyond the brush tripping zone, the magnet 22 may be deenergized and may now be used in the release of a brush set of another switch. When it is desired to restore the switch to 85 its normal position, the down-drive magnet 17 of the operated switch will be energized. This will remove the pawl 16 from operative engagement with the bar 8 and will simultaneously clamp the bar 8 between the down-drive drum 9 and the roller 11. As the switch approaches its normal position, the restoring lever 5 of the operated controlling member 3 will engage the rod 19 and will thus restore the spacing members 6 to a 90 position between the innermost brushes of the set whereby the brushes will be rendered inoperative.

What is claimed is:

1. In a telephone exchange system, a plurality of independently movable switches, a normally inactive brush on each of said switches, and a tripping device common to said switches for rendering active any of said brushes.

2. In a telephone exchange system, a plurality of independently movable switches, a plurality of normally retracted brushes on each of said switches, and tripping devices for rendering said brushes active, each tripping device being common to a plurality of said switches.

3. In a telephone exchange system, a plurality of longitudinally movable shafts, a plurality of normally inactive brush sets on each of said shafts, and tripping devices for rendering said brush sets active, each tripping device being common to all of said shafts.

4. In a telephone exchange system, a plurality of substantially parallel shafts, a plurality of normally inactive brushes on each of said shafts, and trip rods adjacent to all of said shafts for rendering said brushes active, each trip rod being common to 120 a plurality of said shafts.

5. In a telephone exchange system, a plurality of shafts, a plurality of brush sets on each of said shafts, brush-controlling devices, one for each brush set normally main- 125

taining said brushes in inactive position, trip rods extending adjacent to said controlling devices, each trip rod being common to a plurality of shafts, and means carried by 5 said rod adapted to coöperate with said controlling devices to release a desired set of brushes.

6. In a telephone exchange system, a plurality of longitudinally movable brush 10 shafts arranged in substantially parallel relation to each other, a plurality of brush sets on each of said shafts, a controlling device for each brush set normally retaining the brushes thereof in inactive position, and trip 15 rods extending adjacent to said controlling devices, each trip rod being common to the corresponding controlling devices on a plurality of said shafts.

7. In a telephone exchange, a group of 20 switches, each having a plurality of brush sets, and tripping devices equal in number to the greatest number of brush sets on any one switch, each tripping device being adapted to coöperate with any correspond- 25 ingly positioned brush set on said brushes.

8. In a telephone exchange system, a group of switches, each having a like plurality of brush sets, and trip rods equal in number to the brush sets on any one of said 30 switches, each trip rod being adapted to coöperate with the correspondingly positioned brush set on each switch.

9. In a telephone exchange system, a plurality of longitudinally movable brush 35 shafts, each having a like plurality of brush sets, a controlling device for each set normally maintaining the brushes thereof in inactive position, and trip rods equal in number to the number of brushes on any one 40 switch, each trip rod being arranged to coöperate with the correspondingly positioned controlling device on any of said switches.

10. In a telephone exchange system, a plurality of switch shafts arranged substan-

tially parallel in the same plane, each shaft 45 having a plurality of brush sets, a controlling device for each brush set normally maintaining the brushes thereof in inactive position, trip rods extending at right angles to said shafts but parallel to the plane there- 50 of, and means carried by said rod arranged to coöperate with the correspondingly positioned controlling device on any of said shafts to release the brushes thereof.

11. In a telephone exchange system, a 55 plurality of switch shafts arranged substantially parallel in the same plane, each shaft having a plurality of brush sets, a controlling device for each brush set normally maintaining the brushes thereof in inactive 60 position, trip rods extending at right angles to said shafts but parallel to the plane there- 65 of, said trip rods being equal in number to the greatest number of brush sets on any one shaft, and means carried by said trip rods arranged to coöperate with the correspondingly positioned controlling device on any of said shafts to release the brushes thereof.

12. In a telephone exchange system, a plurality of longitudinally movable switch 70 shafts arranged substantially parallel in the same plane, each shaft carrying a plurality of brush sets, a controlling lever for each brush set normally holding the brushes thereof in inoperative position, trip rods ex- 75 tends at right angles to said shafts but parallel to the plane thereof, said trip rods being equal in number to the number of brush sets on one of said shafts, and catches carried by said trip rods, one for each ad- 80 jacent brush set, arranged to coöperate with the correspondingly positioned controlling levers of said sets to release the brushes thereof.

In witness whereof, I hereunto subscribe 85 my name this 5th day of June, A. D., 1915.

JAMES L. McQUARRIE.
